ULTRA HIGH FREQUENCY OSCILLATOR

Ilia E. Mouromtseff, Montclair, and George M. Dinnick, Bloomfield, N. J., assignors to Westinghouse Electric & Manufacturing Company, East Pittsburgh, Pa., a corporation of Pennsylvania

Application October 9, 1940, Serial No. 360,367

13 Claims. (Cl. 250—27.5)

Our invention relates to discharge devices and especially to ultra-high frequency oscillators.

An object of the invention is to eliminate the natural and uncontrollable feed-back through the plate-to-grid capacitance in ultra-high frequency oscillators and to replace it with an external feed back which can be controlled.

Another object of the invention is to effectively screen the high voltage on the anode from the cathode and control grid.

Another object of the invention is to have the anode in an oscillator as part of a hollow body or cavity resonator.

Other objects and advantages of the invention will be apparent from the following description and drawings in which:

Fig. 1 is a view principally in cross section of a discharge device embodying our invention.

Figs. 2, 3, and 4 are cross-sectional views on the respective lines II—II, III—III and IV—IV of Fig. 1.

Fig. 5 is a view mainly in cross section of a modification of Fig. 1.

Fig. 6 is a view on lines VI—VI of Fig. 5.

In ultra-high frequency oscillators the problem of the tube design is closely interconnected with the circuit design. One of the most serious impediments in such oscillators is the natural feed-back through the plate-to-grid capacitance which produces the result that the grid excitation cannot be directly controlled to the best advantage for operation either in the amplitude or in the phase of the grid.

It is one of the objects of our invention to eliminate this uncontrollable feed-back from the plate or anode to the control grid through the tube and to replace it by an external feed back which can be controlled in phase and amplitude.

We also desire to utilize extremely high voltages on the anode, even up to 15,000 volts; and it is an additional object of our invention to effectively screen this high voltage from the other parts of the device.

In Fig. 1 is disclosed a preferred embodiment of our invention in which we have designed a twin tube with a cathode and control grid structure at each end of the device. For this twin tube structure we construct our anode 10 as a hollow pipe with closed ends 11 and 12 acting as the active anode surfaces. The anode has a side opening 13 to which is attached an integral or welded pipe 14 for the entrance of a cooling fluid to the interior of the anode. The anode is preferably longitudinally divided by a plate 15 having central opening 16 to which is at-

tached an inlet pipe 17 for the cooling fluid. The dividing plate 15 has openings 18 at either end for the cooling fluid, such as water, to flow around and out the pipe 14. These two pipes, 14 and 17, are enclosed by a metal tube 19 and this tube is flanged out at 20 so as to be sealed to a reentrant tube of insulation, such as borosilicate glass.

Attached to this insulation is a hollow metal container 22 to form a hollow body or cavity resonator. This hollow body resonator is substantially symmetrical about the anode and has an end 23 parallel and slightly spaced from the anode face 11, and another end 24 parallel to 15 and slightly spaced from the other anode face 12. Both the end 23 and the end 24 are perforated at 25 and 26 for the passage of electrons to the anode faces. The perforated ends 23 and 24 are thin and flexible so that their spacing from the anode faces may be easily adjusted.

Such an adjustment may be by a plate 27 welded to the outer portion of the end 23 and having therethrough adjusting bolts 28 secured to another plate 29, in turn secured to the main portion of the hollow body resonator 22. A similar adjusting arrangement 27', 28' and 29' is located at the other end of the tube to adjust the end 24 in relationship to the anode face 12.

Spaced in front of the perforated end 23 of 30 the hollow body resonator is a control grid 30, and spaced still further is a cathode 31. This cathode is illustrated in its preferred form in Fig. 3 and comprises a thin plate of metal bent to form a flat face 32. This flat face 32 has 35 longitudinal slots 33 extending across the face of the cathode. The ends 34 and 35 of this face are bent downward to contact the cathode leads 36 and 37 extending through a cup-shaped insulation 38, preferably of borosilicate glass, enclosing the cathode and grid arrangement. The slots reduce the cross-sectional area of the front face of the cathode and increased resistance causes the slotted portion of the cathode to rise to the desired temperature to produce electrons from the front face of the cathode. Other types of cathodes may be used if desired, such as coated, indirectly heated, resistance wires, etc. The illustrated cathode, however, is especially adapted to provide a form of electron emission 40 to be acted on by the other elements of the device. The cup-shaped insulation may be sealed to a tubular member 39 welded to the adjusting plate 27. The grid plate 30 is preferably connected by a plurality of rods 40 symmetrically arranged about the cathode structure and pass-

ing through the insulation cup 38 to a ring 41 welded to each of the rods in turn.

At the other end of the tube is a similar arrangement of grid plate 30', cathode 31', and grid rod connections 40' to a connecting ring 41'. We prefer to provide an adjustable external feed-back from the hollow body resonator to the control grid of the device. Preferably at the central portion of the hollow body resonator we secure a pipe 50, and attached to the inner surface of the hollow body resonator at an edge of this pipe, a conductor 51 forming a loop 52 to enclose electromagnetic lines of force therein and having its other end passing axially through the pipe, and a closed insulation plug 53 to form an exterior loop 54 that is secured to the edge of the short pipe 50 at 55.

A similar loop 56 is placed adjacent this loop 54 and made adjustable in regard to the spacing therewith. This loop 56 is connected by a concentric transmission line formed of a pipe 57 connected to one end of the loop 56 and an axial conductor 58 extending through the center of the pipe. The axial conductor and the pipe are connected to another loop 59 adjacent a loop 60 formed by a conductor connected to one end of a cathode lead 36 and at the other end to the ring 41 secured to the grid conductor rods 40. The loops 59 and 60 are adjustable in spacing. The length of the transmission line formed by the pipe 57 and conductor 58 may be made flexible and adjustable. The pipe can be of mesh and the conductor have one or more sections slideable on other section. A similar external feed-back may be applied to the grid and cathode structure 30' and 31', if desired.

As previously mentioned, we apply a very high voltage to the anode structure which may be anywhere up to 15,000 volts or more. The hollow body resonator effectively screens this high voltage from the cathode and control grid structure and permits the use of tens of thousands of volts on the anode. The electron stream produced by the heating of the cathode is controlled by the grids 30 and 30'. These grids preferably permit the electrons to arrive in bunches at the openings 25 and 26 of the hollow body resonator. The electron bunches traversing the space between the openings and the anodes will cause the hollow body to oscillate. The adjustment of the flexible perforated walls changes the frequency of the resonator and must be such as to have the electron bunches arrive at the anode at the proper part of an oscillation cycle to give an optimum operation. The phase and amplitude of grid feed back is regulated by the length and spacing between the extended loops.

In Fig. 5 we have disclosed a device similar to that of Fig. 1 except that we have made a further refinement in the cathode and grid structure. In place of the insulating cups 38 and 38' enclosing cathode and control grid structure, we provide reentrant insulating portions 70 and 70'. This insulating structure is sealed to a metal tube 71 welded to a conductive shell in the form of a tubular metal casing 72. The inner end of this tubular metal casing has a perforated control grid structure 73 spaced and parallel to the perforated openings 25 in the adjacent end 23 of the hollow body resonator. The other outer end of the tubular casing 72 is closed by a flexible metal sheet 74 whose position can be adjusted by any suitable means as by the screw disclosed.

The cathode 75 is preferably similar to that of the cathode 31 in Fig. 1. The rods 76 and 77, 75

however, extend towards the outer end of the tube 72 and have located on their ends two metal pieces 78 and 79 spaced from the end flexible plate 74 a distance approximating the distance of the cathode 75 from the control grid 73. Spacing of this flexible end plate 74 from these two pieces of metal 78 and 79 is adjusted to produce capacity therebetween equivalent to the capacity between the control grid 73 and the cathode 75.

10 The cathode connections 80 and 81 are taken off through insulation 82 in a side tube 83. The hollow tube 72 has a loop 84 preferably located at a central portion and this loop has one end passing axially through insulation 85 in a short pipe 86, and both of these are connected to form another loop 87. The cathode and control grid on the opposite side are preferably similarly constructed, as illustrated with prime numbers, attached to the corresponding structure just described in reference to the left-hand cathode and control grid structure.

15 The transmission concentric pipe line formed by the pipe 57 and axial conductor 58 may be fed back to either the loop 81 of the left-hand cathode and grid structure, or the loop 87' of the right-hand cathode and grid structure, or to both. If both are connected a second transmission line 57', 58' may be coupled to the loop 55 or be coupled to a duplicate of internal loop 52 and external loop 55 of the hollow body resonator.

20 In Fig. 5 we have disclosed a further refinement of our ultra-high frequency oscillator in which the control grid and cathode are made parts of a hollow body or cavity oscillator.

25 While other metals can be used we prefer to make the hollow resonator parts of copper, the metal portions sealed to glass of nickel-cobalt-iron alloy sold under the trade name "Kovar" and the adjustable plates 27, etc., of a nickel-copper alloy sold under the trade name of "Monel."

30 We claim:

1. An electric discharge device comprising anode means including a hollow-body resonator, a cathode, and another hollow-body resonator enclosing said cathode and constituting an electrode for controlling the discharge between said anode and cathode.

45 2. An electric discharge device comprising anode means including a hollow-body resonator, a cathode, and another hollow-body resonator tuned to the same frequency as said first named resonator enclosing said cathode and constituting an electrode for controlling the discharge between said anode and cathode.

50 3. An electric discharge device comprising anode means including a hollow-body resonator, a cathode, and another hollow-body resonator enclosing said cathode and constituting an electrode for controlling the discharge between said anode and cathode, and coupling means between said resonators.

55 4. An electric discharge device comprising anode means including a hollow-body resonator, a cathode, and another hollow-body resonator enclosing said cathode and constituting an electrode for controlling the discharge between said anode and cathode, and means for deriving radiant energy from said other resonator.

60 5. A discharge device comprising an elongated anode, a hollow body resonator enclosing said anode and having openings adjacent the ends of said anode and a cathode and control grid ad-

jacent each of said openings on the exterior of said hollow body resonator.

6. A discharge device comprising an anode, a hollow body resonator having openings therethrough for the passage of electrons to said anode, a cathode and control grid structure, said control grid structure comprising a metal container having openings adjacent said openings in the hollow body resonator and an external feed-back connection from said hollow body resonator to the metal container of said control grid structure, said external feed-back connection comprising sections of concentric pipe transmission line, said concentric pipe transmission line sections having end loops, said end loops being adjustable in spacing from one another.

7. A discharge device comprising an anode and a structure including a cathode and grid, said structure comprising a hollow conductive shell having openings at one portion thereof forming said grid, said cathode being within said shell and adjacent said openings, and conductive pieces conductively connected to said cathode and adjacent another portion of said shell for balancing the capacity between said cathode and the grid.

8. A discharge device comprising an anode and a structure including a cathode and grid, said structure comprising a hollow conductive shell having openings at one portion thereof forming said grid, said cathode being within said shell and adjacent said openings, and conductive pieces conductively connected to said cathode and adjacent another portion of said shell for balancing the capacity between said cathode and the grid, the spacing between said other portion of said shell and the adjacent conductive pieces being adjustable.

9. A discharge device comprising an anode and a structure including a cathode and grid, said structure comprising a hollow tube having one end with openings therethrough forming said grid, the other end of the tube being closed, insulation in a side opening in said tube, connections sealed through said insulation, a cathode adjacent said end with openings and connected to said connections and extensions from said connections towards the closed end of said tube, whereby the capacity between said cathode and grid is substantially balanced by the capacity between said extensions and the closed end of the tube.

10. A discharge device comprising an anode and a structure including a cathode and grid, said structure comprising a hollow tube having one end with openings therethrough forming said grid, the other end of the tube being closed, insulation in a side opening in said tube, connections sealed through said insulation, a cathode adjacent said end with openings and connected to said connections and extensions from said connections towards the closed end of said tube, whereby the capacity between said cathode and grid is substantially balanced by the capacity

between said extensions and the closed end of the tube, said closed end of the tube being flexible and means for adjusting the spacing between said flexible closed end and said extensions.

5 11. A discharge device comprising an anode and a structure including a cathode and grid, said structure comprising a hollow tube having one end with openings therethrough forming said grid, the other end of the tube being closed, insulation in a side opening in said tube, connections sealed through said insulation, a cathode adjacent said end with openings and connected to said connections and extensions from said connections towards the closed end of said tube, whereby the capacity between said cathode and grid is substantially balanced by the capacity between said extensions and the closed end of the tube, a hollow body resonator enclosing said anode, and an external feed back coupling said resonator to said hollow tube.

10 12. A discharge device comprising an anode and a structure including a cathode and grid, said structure comprising a hollow tube having one end with openings therethrough forming said grid, the other end of the tube being closed, insulation in a side opening in said tube, connections sealed through said insulation, a cathode adjacent said end with openings and connected to said connections and extensions from said connections towards the closed end of said tube, whereby the capacity between said cathode and grid is substantially balanced by the capacity between said extensions and the closed end of the tube, a hollow body resonator enclosing said anode, and an external feed back coupling said resonator to said hollow tube.

15 13. A discharge device comprising an anode and a structure including a cathode and grid, said structure comprising a hollow tube having one end with openings therethrough forming said grid, the other end of the tube being closed, insulation in a side opening in said tube, connections sealed through said insulation, a cathode adjacent said end with openings and connected to said connections and extensions from said connections towards the closed end of said tube, whereby the capacity between said cathode and grid is substantially balanced by the capacity between said extensions and the closed end of the tube, a hollow body resonator enclosing said anode, and an external feed back coupling said resonator to said hollow tube, said feed-back comprising a loop in said hollow body resonator, a loop in said hollow tube and concentric pipe transmission line connecting said loops, said concentric pipe transmission line having sections with end loops coupling said sections, the spacing between said loops being variable.
